UNITED STATES PATENT OFFICE.

ROBERT W. THORNE, OF LONDON, ONTARIO, CANADA.

PNEUMATIC CARPET-CLEANER.

1,037,081.

Specification of Letters Patent. Patented Aug. 27, 1912.

Application filed February 2, 1911. Serial No. 606,160.

To all whom it may concern:

Be it known that I, ROBERT W. THORNE, a subject of the King of Great Britain, and a resident of the city of London, in the county of Middlesex, in the Province of Ontario, Canada, have invented a new and useful Pneumatic Carpet-Cleaner, of which the following is a specification.

This invention relates to a device for removing dust, dirt and other foul matter from carpets or coverings for floors. And it consists of the improved construction and novel combination of parts of the same as will be hereinafter first fully set forth and described and then pointed out in the claim.

Reference being had to the accompanying drawings forming part of this specification wherein:

Figure 1 is a plan view of my invention. In this view the wire or other reticulated open floor is shown. Fig. 2 is another plan view of my invention. In this view the wire or other reticulated open floor is removed, and a plan view of the sills, funnels, conducting pipes and attachments are shown. Fig. 3 is an end view of my invention. In this view the compressed air tank, the funnels to catch the dust, dirt and other foul matter, and the pipes leading from the funnels to the fan to remove dust, dirt and other impurities, are shown. Fig. 4 shows one of the floor wires adjustably held at one end, and Fig. 5 shows one of the floor wires rigidly held at the other end. Fig. 6 is a side view, and Fig. 7 a front view of the air nozzle and attachments. Fig. 8 is a view of the air nozzle looking at it from the underside.

In the accompanying drawings: 1 indicates the sills of the floor and 2 the open floor made of crossed wires or other reticulated suitable material.

In Fig. 5 one of the wires, *a*, of which the open floor is formed, is shown rigidly secured to the sill 1, by the staples 3, and to the sill 1 at the other side of the open floor, the other end of the wire, *a*, is secured to the eyebolt, as shown in Fig. 4.

5 is a sill board secured to the sill 1 by the bolts 6, and the eyebolt 4 extends through the sill board 5 and is adjustably secured in place by a nut 7 screwed on said eyebolt 4. The crossed wire or other reticulated open floor 2 is thus adjustably secured 55 to the sills 1, being adapted to sag slightly toward its center as shown.

8 are funnels, open at the top, which extend from and are secured at their edges to the sills 1, and these funnels 8 extend slightly below the open floor 2, having the top edges or rims 8' thereof inclined slightly inwardly as shown in Fig. 3. The rims 8' at the mouths of the funnels being inclined toward the transverse line 9' leave spaces or openings 10' for the entrance of air to the exhausting funnels 8.

9 are conducting pipes which communicate with and open into the funnels 8, and 10 is a fan which opens into and communicates with these conducting pipes 9, as shown; and 11 is a well or other body of sanitary water into which the fan 10 empties.

12 is a lever which is shown pivotally secured to the funnel 8, but it may be secured to the sill 1 or other suitable support, which lever 12 operates a valve 13 in the enlargement, *c*, of the funnel 8, when required, which valve 13 shuts off any funnel 8 from the pipe 9 when part of the funnels 8 are not used, in order to concentrate the wind from the conducting pipe 9 to suck the dust, dirt or other impurities down any of the funnels 8.

14 is a door in each of the funnels 8, which is used to get at the inside of said funnels 8 from the underside to sweep or clean them out when desired or for repairs or for any other purpose.

15 is a compressed air tank, situated at any suitable point, the air pressure in which is maintained by an engine and air compressor or by any suitable means.

16 is an air pipe, which pipes the air from said compressed air tank to the nozzle 17, out of which the compressed air passes through a narrow slit, *b*.

18 is a valve in this pipe 16, to permit or prevent the compressed air to pass to the nozzle 17.

The operation which is very simple is as follows: The carpet is laid face down on the wire or other open floor 2, and every particle of dust, dirt, and other impurities are forced from every thread of the carpet by about one hundred pounds air pressure coming from the compressed air tank 15 through the air pipe 16, and out of the slit, *b*, in the nozzle 17 on to the carpet and from the latter into the funnel 8 below, leaving the carpet perfectly sanitary and clean. But if the carpet should be very dirty, it

can be gone over again or it may be turned over and receive another application of air from the same or opposite side, and the air nozzle 17 being in the hands of an operator 5 he can conduct the air to the central or other dirty part of the carpet, as required. The dust, etc., taken from each carpet or the like floor covering, is conducted by the funnels 8 to the pipes 9, and by a fan 10 or other underground suction system, is deposited in a sanitary well 11 outside, which is kept thoroughly disinfected. A device 10 is therefore provided which is very simple, durable and inexpensive to manufacture, 15 and one very efficient in practical use.

Having thus described my invention, I claim:

An apparatus for cleaning fabrics comprising an adjustably-mounted foraminous 20 support for the fabric slightly depressed toward the center thereof, sills upon which

said support is mounted, means for forcing dust downwardly through the fabric, a pair of funnels located therebelow, rims at the mouths of said funnels arranged so as to 25 fill the space between the said sills, the adjacent portions of said rims extending below said sills, forming air entrance openings between said sills and rims, conducting pipes for said funnels extending toward each other, suction pipes communicating with said conducting pipes, a valve in each of said conducting pipes, and independent pivoted means operable from a point above said support for controlling said valve. 30 35

In testimony whereof, I have signed in the presence of the two undersigned witnesses.

ROBERT W. THORNE.

Witnesses:

P. J. EDMUNDS,
S. HARDY.
